UNITED STATES PATENT OFFICE.

JEAN BAPTISTE GIRARD, OF ST. AIMÉ, CANADA, ASSIGNOR OF ONE-HALF
TO P. HUGUES GELINAS, OF ST. HUGUES, CANADA.

WIND-WHEEL.

SPECIFICATION forming part of Letters Patent No. 634,168, dated October 3, 1899.

Application filed February 16, 1899. Serial No. 705,800. (No model.)

To all whom it may concern:

Be it known that I, JEAN BAPTISTE GIRARD, a subject of Her Majesty the Queen of Great Britain, residing at St. Aimé, county of Riche-
5 lieu, Province of Quebec, Canada, have in-
vented certain new and useful Improvements
in Wind-Wheels; and I do hereby declare the
following to be a full, clear, and exact descrip-
tion of the invention, such as will enable oth-
10 ers skilled in the art to which it appertains to
make and use the same.

My invention relates to improvements in
wind-wheels.

The object of my invention is to provide a
15 wind-wheel which can be readily set up and
taken down, which can be readily placed in
position in a boat to serve as a driving power,
and in which the structural parts are simple
and efficient in operation and durable in con-
20 struction.

A further object is to provide a wind-wheel
in which the vanes are held in fixed position,
the angle at which the vanes are held being
such as will allow of the vanes receiving the
25 full force of the air-currents, yet not impeding
the rotary movement of the wind-wheel.

To these and other ends my invention con-
sists in the improved construction and com-
bination of parts hereinafter fully described,
30 and particularly pointed out in the appended
claim.

In the drawings, in which similar numerals
of reference indicate similar parts in all of
35 the views, Figure 1 is a sectional view of a
boat, showing my improved wind-wheel in
position to drive the boat against the wind.
Fig. 2 is a view showing a section of the wind-
wheel. Fig. 3 is a sectional view showing the
outer rim of the wheel. Fig. 4 is an enlarged
40 sectional view showing the manner of fasten-
ing the inner end of the vanes. Figs. 5 and
6 are diagrammatic views showing the man-
ner in which the inclination of the vanes is
secured.

45 In the construction of the wind-wheel it is
essential that the parts be strong and sub-
stantial and of exceeding lightness and ca-
pable of being readily taken apart. It is
therefore the object of my invention to pro-
50 vide a construction in which these features
are found and also to provide a wheel that

can be placed in a boat and connected to the
propeller by suitable mechanism, by means
of which the boat will be driven forward by
the movement of the wheel, the position of 55
the wheel being capable of adjustment by the
steersman in order that the wheel can be held
directly against the wind regardless of the di-
rection of movement of the boat.

1 designates a wind-wheel comprising a cen- 60
tral hub 2, having radiating arms 3. Each
arm 3 is provided with laterally-extending lugs
4, having a hook portion 5, the hook portions
being adapted to receive a segmental portion
6, to which the lower ends of the vanes are 65
attached, the hooks 5 passing into suitable
openings 7, formed in said segmental por-
tions. The outer ends 8 of the arms 3 extend
a short distance beyond the lugs 4 and are
adapted to receive the inner end of the hol- 70
low arms 9, which form extensions of the arms
3, said arms 9 having their outer ends con-
nected to a suitable rim 10, formed in sec-
tions and having a semicylindrical form in
cross-section. Each section of the rim 10 is 75
provided with a series of bars 11, extending
diagonally across the diameter of said section
at an angle of approximately twenty-six and
one-half degrees, (26½°,) said bars forming
the outer connecting means for the vanes 12. 80
The vanes 12 are formed of suitable material,
preferably flexible, and are arranged in such
manner as to have their outer end of greater
width than the inner end, the latter being
connected to suitable cross-bars 13, having a 85
threaded extension 14 adapted to pass through
suitable openings 15, formed in the segmental
portion 6, thus holding the vanes at their
proper angle, the extensions being held in po-
sition by means of nuts threaded on the ends 90
of the extensions 14, allowing of an adjust-
ment of the vanes and also to allow of their
being removed when desired. By this con-
struction it will be readily seen that by re-
moving the vanes from the segmental por- 95
tions the entire outer section may be readily
removed from or put in place on the inner
section, making the wind-wheel easy to trans-
port.

I have heretofore stated that the vanes are 100
located at an angle of approximately twenty-
six and one-half degrees (26½°) and will now

proceed to describe the method by which this angle is obtained and also its advantages.

As shown in Fig. 5, a square is drawn having each of its sides equal to the width of the vane. An arc of a circle is then drawn having its radius equal to one of the sides of the square, the center being placed at one of the meeting points of the square. The square is then bisected and a line drawn from the point used as a center to the meeting point of the line of bisection and the side of the square at the opposite side to that of the point used as a center, the line so drawn cutting the arc, this line being approximately at an angle of twenty-six and a half degrees, (26½°.) As will be seen in Fig. 5, the point of intersection of the line of inclination of the vane and the arc is a short distance from the line of bisection, and as the vane is of a length only equal to the distance between the center used and the arc and the vanes are spaced a distance apart equal to one-half ($\frac{1}{2}$) their width it will be apparent that a space will be formed between the vanes (as best shown in Fig. 6) which will allow of the direct passage of the air-currents. This angle of the vanes has been found to be the most suitable to obtain the greatest effect of the air-currents, inasmuch as the surface is presented at such an angle to receive the full benefit of the air-current, yet which will allow the currents of air to pass through the vane without a great amount of friction, thereby preventing the tendency of the wheel to sag, as is clearly apparent in the case of vanes set at an angle of forty-five degrees (45°) and sixty degrees, (60°,) as shown in Fig. 5.

As the wheel is particularly adapted for use in the propelling of boats, I will now proceed to describe the mechanism used by means of which the boat may be driven forward directly against the wind.

As shown in Fig. 1, the wheel 1 is mounted on a shaft 16, mounted in a bearing 17, formed on the end of a hollow rotatable upright 18. The shaft 16 is provided with a suitable bevel-gear 19, adapted to coact with a similar gear 20, mounted on a vertical shaft 21, mounted within the upright 18. The lower end of the shaft 21 is provided with a bevel-gear 22, adapted to coact with a similar gear 23, mounted on a shaft 24, extending longitudinally of the boat 25, the shaft 24 extending through the stern of the boat and having its rear end provided with a propeller 26 of suitable shape. The lower end of the upright 18 is provided with a suitable worm-gear 27, which is moved by

means of a suitable worm 28, mounted on a rearwardly-extending shaft 29, to the rear end of which is connected an operating-handle 30. A suitable tiller is provided, and the handle 30 is located at a point convenient to the steersman.

From this construction it will be apparent that as the wheel is revolved the propeller 65 will be caused to rotate, thus carrying the boat forward. When the wind is blowing in a direction away from the direction of movement of the boat, the handle 30 is rotated, which through the medium of the worm 28, 70 the worm-gear 27, and the upright 18 causes the bearing to be moved until the desired direction is reached, when the wheel, being in proper position to receive the direct force of the air-currents, will continue to rotate the 75 propeller. When it is desired to stop the boat, the handle 30 is rotated until the vanes present their edges to the wind, when the wheel will cease its movement.

While I have herein shown a preferred form 80 of carrying my invention into effect, yet I do not desire to limit myself to such preferred detail of construction, but claim the right to use any and all modifications thereof which will serve to carry into effect the objects to 85 be attained by this invention in so far as such modifications and changes may fall within the spirit and scope of my said invention.

Having thus described my invention, what I claim as new is—

A wind-wheel, comprising a hub having radiating arms integral therewith, laterally-extending lugs fixed upon said arms and provided with hooks at the extremities thereof, a segmental portion located between said arms, 95 each portion having suitable openings to receive said hooks, hollow arms sleeved upon the ends of said radiating arms, a rim semi-circular in cross-section secured to the outer ends of said hollow arms, diagonally-arranged 100 bars connecting the edges of said rim, flexible vanes secured at their outer ends to said diagonal bars, the inner ends of said vanes being adjustably mounted in suitable openings in said segmental portions, and means for 105 locking said flexible vanes in their adjusted position, substantially as described.

In witness whereof I have hereunto set my hand in the presence of two witnesses.

JEAN BAPTISTE GIRARD.
